UNITED STATES PATENT OFFICE.

KARL D. SMITH, OF BATTLE CREEK, MICHIGAN, ASSIGNOR TO UNION STEAM PUMP COMPANY, OF BATTLE CREEK, MICHIGAN.

PUMP.

1,246,342.

Specification of Letters Patent. Patented Nov. 13, 1917.

Application filed November 2, 1916. Serial No. 129,118.

To all whom it may concern:

Be it known that I, KARL D. SMITH, a citizen of the United States, residing at Battle Creek, county of Calhoun, State of Michigan, have invented certain new and useful Improvements in Pumps, of which the following is a specification.

This invention relates to improvements in pumps.

10 My improvements relate mainly to the pump cylinder and are especially designed by me for embodiment in liquid pumps for pumping milk and other liquids which necessitate frequent cleaning to keep them in 15 sanitary condition.

The main objects of this invention are:

First, to provide an improved pump cylinder in which the parts are all readily accessible for cleaning.

20 Second, to provide an improved pump in which all the surfaces with which the liquid contacts are machined rendering them easy to clean.

Third, to provide an improved pump 25 which is of large capacity and durable and not likely to get out of repair in use.

Further objects, and objects relating to structural details, will definitely appear from the detailed description to follow.

30 I accomplish the objects of my invention by the devices and means described in the following specification. The invention is clearly defined and pointed out in the claims.

A structure which is a preferred embodiment 35 of my invention is clearly illustrated in the accompanying drawing, forming a part of this specification, in which:

Figure I is a plan view of the cylinder portion of a pump embodying the features 40 of my invention.

Fig. II is a plan view with the face plate or cover plate removed showing the arrangement of the ports and passages and also the disposition of the valves.

45 Fig. III is a detail vertical section on a line corresponding to line 3—3 of Figs. I, II and V, showing the arrangement of the intake passages and ports.

Fig. IV is a detail vertical section on a 50 line corresponding to line 4—4 of Figs. I and II, showing the arrangement of the outlet passages and ports.

Fig. V is a detail transverse section on a line corresponding to line 5—5 of Figs. I,

II and III, showing the relation of the inlet and discharge ports to each other and to the cylinder bore.

Fig. VI is a detail transverse section taken on a line corresponding to line 6—6 of Figs. I, II, III and IV, showing the arrangement 60 of the inlet and discharge passages in the cylinder.

In the drawing similar reference characters refer to similar parts throughout the several views, and the sectional views are 65 taken looking in the direction of the little arrows at the ends of the section lines.

Referring to the drawing, the pump cylinder 1 illustrated is a casting having a head 1' formed integral therewith. The cylinder is provided at its inner end with a flange 1'' for removably mounting the cylinder upon the head plate 2 carried by the yoke 2'.

The piston 3, which is shown conventionally, is provided with a piston rod 4 reciprocating through the stuffing box 5. The cylinder flange is adapted to receive the attaching bolts by which it is removably secured in position, the bolts not being illustrated.

The cylinder 1 has a flat face 6 at one side, the face being preferably perfectly flat, as shown, so that it may be readily machined. Leading from one side of the cylinder and parallel with the face 6 is an inlet passage 7, the passage being formed by drilling. This passage is provided with a pair of spaced delivery ports 8 and 8' which open at the face of the cylinder, these being 80 formed by bores from the face positioned to intersect the bore forming the inlet passage 7.

The inlet passages 9 and 9' and the outlet passages 12 and 12' are disposed in opposed pairs at the ends of the cylinder and transversely of the cylinder bore. These passages are also preferably drilled and are disposed so that the outer sides of their bores are tangential to the bore of the cylinder, thus avoiding any shoulders or projections where the port bores enter the cylinder bore.

The ports 8 and 8' of the inlet passage 7 are provided with valves 13 and 13'. These 105 valves seat in the face of the cylinder which is preferably beveled around the ports, as shown. The stems of these valves slidably

fit the ports and serve to guide the valves in their movement.

The discharge ports 12 and 12' are provided with valves 14 and 14', respectively, 5 which also seat on the face of the cylinder, all the valves being duplicates so that they may be used interchangeably.

The face plate 15 is removably mounted on the face 6, the cylinder being provided 10 with projecting threaded studs 16 arranged through perforations in the plate and clamped in position by means of the winged nuts 17. This face plate is provided with channel-like recesses in its inner face which 15 coat with the face of the cylinder to provide valve chambers and connecting passages for the ports. The plate is provided with recesses 18 and 18' which connect the ports 8 and 8' with the ports 9 and 9', respectively. The plate is also provided with a 20 passage recess 19 which connects both of the ports 12 and 12' with the outlet passage 10.

By forming the inlet and outlet passages in the cylinder 1 it is unnecessary to 25 disturb the cylinder connections when the plate 15 is removed. When the plate 15 is removed all of the valves may be freely removed and as these valves are interchangeable they may be conveniently replaced in 30 operative position. The passages are all arranged so that they are accessible for cleaning and, as stated, they are preferably formed by drilling so that their walls are smooth and readily cleaned. The cylinder 35 is mounted so that it can be quickly removed and drawn off the piston, thus adapting the structure for pumping milk or other liquids which necessitate frequent cleaning.

With the parts thus arranged the action 40 of the pump is as follows: In Fig. III the parts are illustrated with the piston in its outstroke. On this outstroke the liquid in front of the piston is forced through the port 12 past the valve 14 to the discharge 45 10. The same movement draws a charge through the passage 7 past the valve 13' and through the port 9' of the cylinder. On the return stroke the charge thus drawn in is discharged through the outlet port 12' past 50 the outlet valve 14' to the discharge 10.

By this simple arrangement I secure a double acting pump in which the parts are few and one which, as stated, is readily assembled and disassembled and kept in a 55 sanitary condition.

I have illustrated and described my improvements in detail in the form in which I have embodied the same for the market. I have not illustrated or described certain 60 modifications in structural details which might be desirable to adapt my invention to various pumps and pumps designed for other purposes as I believe the disclosure

made will enable those skilled in the art to which this invention relates to embody or 65 adapt the same as conditions may render desirable.

Having thus described my invention, what I claim as new and desire to secure by Letters Patent, is:

1. In a pump, the combination of a cylinder having a flat face at one side and inlet and outlet ports opening in said flat face and disposed in opposed pairs at the ends of the cylinder and transversely of the cylinder bore and so that the outer sides of the port bores are tangential thereto, said cylinder being also provided with an inlet passage having a pair of ports opening in said face between the said cylinder inlet ports 80 and with an outlet passage having a port opening in said cylinder face between said cylinder discharge ports, a plate fitted upon said face for ready removal and provided in its inner side with recesses coacting with 85 said face to provide valve chambers and connecting passages for said inlet passage ports and said cylinder inlet ports and said cylinder discharge ports and said outlet passage port, and valves for said inlet passage ports and said cylinder discharge ports seating on said cylinder face and provided with guide stems disposed in such ports, said valves being freely removable and interchangeable when said plate is removed. 95

2. In a pump, the combination of a cylinder having a flat face at one side and inlet and outlet ports opening in said flat face and disposed in opposed pairs at the ends of the cylinder and transversely of the cylinder 100 bore and so that the outer sides of the port bores are tangential thereto, said cylinder being also provided with an inlet passage having a pair of ports opening in said face between the said cylinder inlet ports and with an outlet passage having a port opening in said cylinder face between said cylinder discharge ports, a plate fitted upon said 105 face for ready removal and provided in its inner side with recesses coacting with said face to provide connecting passages for said inlet passage ports and said cylinder inlet ports and said cylinder discharge ports and said outlet passage port, and cylinder inlet 110 and discharge valves. 115

3. In a pump, the combination of a cylinder having a flat face at one side and inlet and outlet ports opening in said flat face, said cylinder being also provided with an inlet passage having a pair of ports opening in said face between the said cylinder inlet ports and with an outlet passage having a port opening in said cylinder face between said cylinder discharge ports, a plate fitted upon said face for ready removal and provided in its inner side with recesses co- 120 125

- acting with said face to provide valve chambers and connecting passages for said inlet passage ports and said cylinder inlet ports and said cylinder discharge ports and said outlet passage port, and valves for said inlet passage ports and said cylinder discharge ports seating on said cylinder face and provided with guide stems disposed in such ports, said valves being freely removable and interchangeable when said plate is removed.
4. In a pump, the combination of a cylinder having a flat face at one side and inlet and outlet ports opening in said flat face, said cylinder being also provided with an inlet passage having a pair of ports opening in said face between the said cylinder inlet ports and with an outlet passage having a port opening in said cylinder face between said cylinder discharge ports, a plate fitted upon said face for ready removal and provided in its inner side with recesses coacting with said face to provide connecting passages for said inlet passage ports and said cylinder inlet ports and said cylinder discharge ports and said outlet passage port, and cylinder inlet and discharge valves.
5. In a pump, the combination of a cylinder faced at one side and having inlet and outlet ports opening in said face, said cylinder being also provided with an outlet passage having a port opening in said cylinder face, a removable face plate provided with recesses coacting with said face to provide valve chambers and connecting passages for said inlet passage ports and said cylinder inlet ports and said cylinder discharge ports seating on said cylinder face and provided with guide stems disposed in such ports, said valves being freely removable and interchangeable when said plate is removed.
6. In a pump, the combination of a cylinder faced at one side and having inlet and outlet ports opening in said face, said cylinder being also provided with an inlet passage having a pair of ports opening in said face and with an outlet passage having a port opening in said face, a removable face plate provided with recesses coacting with said face to provide valve chambers and connecting passages for said inlet passage ports and said cylinder inlet ports and said cylinder discharge ports and said outlet passage ports, and valves for said inlet passage ports and said cylinder discharge ports seating on said cylinder face.
7. In a pump, the combination of a cylinder faced at one side and having inlet and outlet ports opening in said face, said cylinder being also provided with an inlet passage having a pair of ports opening in said face.
8. In a pump, the combination of a cylinder faced at one side and having inlet and outlet ports opening in said face, said cylinder being also provided with an inlet passage having a pair of ports opening in said face, a removable face plate provided with recesses coacting with said face to provide valve chambers and connecting passages for said inlet passage ports and said cylinder inlet ports and said cylinder discharge ports seating on said cylinder face.
9. In a pump, the combination of a cylinder faced at one side and having straight inlet and outlet ports opening in said face and disposed in opposed pairs at the ends of the cylinder and transversely of the cylinder bore and so that the outer sides of the port bores are tangential thereto, a removable face plate provided with recesses coacting with said face to provide valve chambers and passages communicating with said ports, and inlet and discharge valves seating on said face.
10. In a pump, the combination of a cylinder having a flat face at one side and having separate inlet and outlet ports opening in said flat face, a removable face plate provided with recesses coacting with said face to provide passages communicating with said ports, and inlet and discharge valves, said inlet valves opening outwardly.
11. In a pump, the combination of a cylinder faced at one side and having inlet ports opening in said face, a removable face plate provided with recesses coacting with said face to provide valve chambers and passages communicating with said ports, and inlet valves seating on said face.
12. In a pump, the combination of a cylinder faced at one side and having cylinder inlet and outlet ports opening in said face and inlet and outlet passages having ports opening in said face, a removable face plate provided with recesses coacting with said face to provide valve chambers and passages communicating with said ports, and inlet and discharge valves seating on said face, all coacting as specified.
13. In a pump, the combination of a cylinder faced on one side and having a cylinder port opening in said face and a passage having a port opening in said face, a re-

movable face plate provided with a recess
coacting with said face to provide a valve
chamber and passage communicating with
said port, and an outwardly opening valve
5 for said port.

14. In a pump, the combination of a cyl-
inder provided with a valve plate face on
one side and having a cylinder port open-
ing in said face and a passage having a port
10 opening in said face, a removable face plate
coacting with said face to provide a valve

chamber and passage communicating with
said port, and an outwardly opening valve
for said port.

In witness whereof, I have hereunto set 15
my hand and seal in the presence of two
witnesses.
